UNITED STATES PATENT OFFICE.

JOHN KELLY, OF JAMAICA PLAIN, MASSACHUSETTS.

SEWER-CLEANING APPARATUS.

No. 906,034.

Specification of Letters Patent.

Patented Dec. 8, 1908.

Application filed September 8, 1908. Serial No. 451,941.

To all whom it may concern:

Be it known that I, JOHN KELLY, a citizen of the United States, residing at Jamaica Plain, in the county of Suffolk and State of Massachusetts, have invented new and useful Improvements in Sewer-Cleaning Apparatus, of which the following is a specification.

This invention relates to improvements in sewer cleaning apparatus of that class in which a device is moved longitudinally within the sewer by means of ropes, chains or the like connected to devices located in the manholes, and the object is to provide in an apparatus of the class described an expandible structure adapted to be adjusted to fit manholes of various sizes and adapted to be forcibly expanded to bear against opposite abutments within the manhole, to which structure the movable cleaning device is connected by suitable connections such as a rope and pulley.

The invention consists in the combination and arrangement of parts set forth in the following specification and particularly pointed out in the appended claims.

Referring to the drawings: Figure 1 is a longitudinal vertical section of a sewer and two manholes thereof showing my apparatus arranged therein, the apparatus being in elevation. Fig. 2 is an enlarged plan section taken on line 2—2 of Fig. 1. Fig. 3 is a sectional elevation taken on line 3—3 of Fig. 2. Fig. 4 is a detail end elevation of the semi-cylindrical yoke.

Like numerals refer to like parts throughout the several views of the drawing.

In the drawing, 5 is a sewer pipe leading into two manholes 6, 6. In the sewer pipe 5 is located a cleaning device 7 adapted to be moved longitudinally within the sewer pipe 5, said device being of any suitable or desired construction. Within each of the manholes 5 is located an expandible structure 8 and said structures being identical in construction the following description of the left hand structure will suffice for both, it being understood that said structures are placed so as to face in opposite directions.

50 The structure 8 comprises two yokes 9 and 10 located at opposite sides, respectively, of the manhole 6 adjacent to the orifices of the sewer pipe. The yoke 9 is preferably U-shaped in form as seen in Fig. 2 and extends

within the sewer pipe at the orifice of which 55 it is located, said yoke having fast thereto an eye bolt 11 which passes therethrough and is secured by means of nuts 12. Connected to the eye bolt 11 is a pulley block 13 constituting a part of a tackle comprising 60 a rope 14 secured to said block and passing through a block 15 connected to the cleaning device 7, thence back through the block 13 and thence upwardly through the opening of the manhole 6. 65

It will be understood that the tackle just referred to is preferably in duplicate, there being one connected to each end of the cleaning device 7.

The yoke 10 which may be made and preferably is semi-cylindrical in form, is connected by means of bolts 16, 16 to flat rods or plates 17, 17 which are adapted to rest upon shelves 18, 18, respectively, the upper faces of said shelves on which said rods rest 75 lying in a plane located at approximately the height of the axis of the sewer pipe 5. Each of the plates 17 is provided with a plurality of holes corresponding to holes 19 formed in plates or rods 20, 20 also 80 adapted to rest upon the shelves 18, 18, respectively, said plates or rods being secured to each other in pairs by means of bolts 21, 21 and bolts 22, 22 passing therethrough.

The plates 20, 20 are provided, respectively, with cylindrical shanks 23 23 having screw-threaded engagement with turn buckles 24, 24, said turn buckles also having screw-threaded engagement with rods 25, 25, it being understood that said turn buckles 85 have right and left screw-threaded engagement with said rods and said shanks, respectively. The rods 25, 25 pass through the yoke 9 and are secured thereto by means of oppositely placed nuts 26 and 27 having screw-threaded engagement therewith. Check nuts 28 and 29 having screw-threaded engagement with the rods 25 and shanks 23, respectively, are adapted to be screwed against opposite ends, respectively, of the 90 turn buckles 24 to lock said turn buckles 95 against rotation.

When the expandible structure 8 is placed in the manhole it is first roughly adjusted to the proper size by removing the bolts 21 and 105 22 and properly placing the plates 17 and 20, after which said bolts are replaced in the proper holes and secured therein. The turn

buckles 24 are then rotated in the proper direction to force the yokes 9 and 10 in opposite directions, respectively, against opposite abutments in the manhole 6, thereby 5 firmly securing the structure in place.

The apparatus having been installed, as seen in Fig. 1, the cleaning device 7 may then be moved longitudinally through the sewer pipe by pulling on the two ropes 14 10 alternately. The yoke 10 is so constructed and arranged that the cleaning device 7 may be drawn thereunder into the space between said yoke and the yoke 9, after which said device may be emptied of collections of 15 matter carried thereby.

If desired, I may provide a roll 30 journaled on the inner or under side of the yoke 10 to prevent chafing of the rope while reaving the same through the pulleys.

20 It will be understood that the expandible structure 8 may be adjusted through a wide range of sizes to fit various sizes of manholes and when in place forms a perfectly rigid support for the pulley block 13.

25 In some cases it may be desirable on account of the small size of the opening of the manhole to fold the yoke 10 down between the side members of said structure and this may be done by removing the bolts 22, 22 and 30 swinging said yoke between said members.

Having thus described my invention, what I claim and desire by Letters Patent to secure is:

1. An apparatus for cleaning sewers, having in combination, a device adapted to be placed within a sewer manhole, said device being horizontally expandible, whereby the same may be adjusted to bear against horizontally opposite abutments, respectively, 35 within said manhole adjacent to the sewer pipe orifices, a device adapted to be placed in the sewer pipe, and means operatively connecting said device, whereby said last-named device may be moved longitudinally 40 within the sewer.

2. An apparatus for cleaning sewers, having in combination, a device adapted to be placed within a sewer manhole, said device comprising two relatively horizontally movable parts adapted to be adjusted to bear against horizontally opposite abutments, respectively, within said manhole adjacent to the sewer pipe orifices, means to hold said parts in fixed relation with each other, a device adapted to be placed in the sewer pipe, and means operatively connecting said devices, whereby said last-named device may be moved longitudinally within the sewer.

3. An apparatus for cleaning sewers, having in combination, a device adapted to be placed within a sewer manhole, said device comprising two relatively horizontally movable parts, means to force said parts against horizontally opposite sides, respectively, of 65 said manhole adjacent to the sewer pipe

orifices, a device adapted to be placed in the sewer pipe, and means operatively connecting said devices, whereby said last-named device may be moved longitudinally within the sewer.

4. An apparatus for cleaning sewers, having in combination, a device adapted to be placed within a sewer manhole, said device comprising two relatively horizontally movable parts, a screw adapted to move one of 70 said parts relatively to the other to force said parts against horizontally opposite sides, respectively, of said manhole adjacent to the sewer pipe orifices, a device adapted to be placed in the sewer pipe, and means 75 operatively connecting said devices, whereby said last-named device may be moved longitudinally within the sewer.

5. An apparatus for cleaning sewers, having in combination, an expandible device 80 adapted to be placed within a sewer manhole, said device comprising two relatively horizontally movable parts adapted to be adjusted relatively to horizontally opposite sides, respectively, of said manhole adjacent to the sewer pipe orifices, means to hold said parts in fixed relation with each other, a screw adapted to expand said device to cause the same to bear against opposite sides, respectively, of said manhole, a device adapted to be placed in the sewer pipe, and means 85 operatively connecting said devices, whereby said last-named device may be moved longitudinally within the sewer.

6. An apparatus for cleaning sewers, having in combination, an expandible device 100 adapted to be placed within a sewer manhole, means to expand said device horizontally, whereby the same may be caused to bear against horizontally opposite sides, respectively, of said manhole adjacent to the sewer pipe orifice, a device adapted to be placed in the sewer pipe, and means operatively connecting said devices, whereby said last-named device may be moved longitudinally within the sewer.

7. In an apparatus for cleaning sewers, a structure adapted to be placed within a sewer manhole, said structure comprising a device adapted to be placed against an abutment at one side of said manhole, a second device adapted to be placed against an abutment at the opposite side of said manhole, one of said devices being expandible, and means to independently expand the other of 115 said devices to cause said devices to bear against said abutments, respectively.

8. In an apparatus for cleaning sewers, a structure adapted to be placed within a sewer manhole, said structure comprising a 120 device adapted to be placed against an abutment at one side of said manhole, a second device adapted to be placed against an abutment at the opposite side of said manhole, one of said devices comprising two rela- 125

tively movable parts, means to hold said parts in fixed relation with each other, and a nut having right and left hand screw-threaded connection with said devices, respectively, whereby said devices may be caused to bear against said abutments, respectively.

In testimony whereof I have hereunto set my hand in presence of two subscribing witnesses.

JOHN KELLY.
